UNITED STATES PATENT OFFICE.

RUDOLPH A. BREITENFELD, OF MADISON, WISCONSIN.

WINDOW SHADE AND CURTAIN ADJUSTER.

No. 895,237.

Specification of Letters Patent.

Patented Aug. 4, 1908.

Application filed October 21, 1907. Serial No. 398,445.

To all whom it may concern:

Be it known that I, RUDOLPH A. BREITENFELD, a citizen of the United States, residing at Madison, in the county of Dane and State 5 of Wisconsin, have invented a new and useful Improvement in Window Shade and Curtain Adjusters, of which the following is a specification.

My invention relates to an improved and 10 adjustable method for attaching a shade roller of the ordinary spring acting type, and a curtain rod to the shade and curtain adjuster described in my Letters Patent Number 865,007, issued September third, 1907.

15 My improvement is illustrated in the accompanying drawings, in which:

Figure 1 is an isometric projection of the vertical adjusting elements described in my former patent above noted, and showing in 20 addition, the adjustable bracket device for attaching the shade roller and curtain rod to the vertical adjuster, and a shade roller and curtain rod. Fig. 2 is an isometric projection of the adjustable bracket device. Fig. 3 25 is a side elevation of an improved device for attaching the shade roller and curtain rod to the bracket, and a shade roller and curtain rod. Fig. 4 is an isometric projection of the free spindle end of the shade roller, with the free spindle and its fastening 30 device in position. Fig. 5 is a front view of a portion of a window casing, with my improved shade and curtain adjuster attached to front face of casing. Fig. 6 is a front view of a portion of a window casing, with my improved 35 shade and curtain adjuster attached to the inner face of casing. Fig. 7 is a side view of the elements shown in Fig. 5, the view being taken from the interior of the casing.

40 In the several views A is the base plate of the adjuster, along which a hollow sliding block B is vertically guided by grooves. This block B can be adjusted to various heights, carrying the shade roller and curtain rod with it. Block B is secured at any given vertical height by a ratchet spring X, within block B making contact with one of the ratchet notches E E in base plate A. A 45 partial rotation of rod C, by the action of cam 50 Y, releases ratchet spring X for lowering shade roller and curtain rod.

55 My improved device for attaching the shade roller and curtain rod to the adjuster is shown by Fig. 2, and consists of a portion F, preferably of open side square section, formed as part of which are the projecting arms G

and H. The preferred construction for these arms is that shown, in which G, which carries the curtain rod I, projects beyond and above H, which carries the shade roller J, 60 thus allowing the shade K to hang between the curtain L and the window, and close to the latter, as shown by Fig. 7.

As shown by Fig. 2, the curtain support arm G has at its outer end a vertical projecting pin N, a similar pin M being formed on the outer end of the shade support arm H.

The curtain rod is provided with two diametral holes, through each of which projects one of the vertical pins N, thus holding the 70 curtain rod in fixed relation with regard to the attaching device, and therefore with the adjuster, as shown by Figs. 1, 5, 6 and 7.

The spring spindle of the shade roller may be attached to the pin M by one of the clips 75 O, Fig. 1, illustrated in my Patent Number 865,007.

An improved method for securing the free spindle end of the shade roller to the bracket, Fig. 2, is shown by Figs. 3 and 4 in which the 80 flattened piece P has formed as part of it the spindle Q, projecting through and working freely in a sleeve R. The spindle Q is headed at its end S, so that it can not pass through sleeve R.

A hole U is provided in P, through which pin M of bracket H passes, as shown by Fig. 4. Formed as part of sleeve R are radial arms V, each of which is formed in a point T parallel to axis of sleeve R. In assembling, 90 these points T are driven into the end of shade roller J, as shown by Fig. 4, so that the axis of shade roller J coincides with axis of spindle Q, a ferrule W preventing splitting of shade roller, and a central hole in end of 95 roller allowing clearance for spindle Q and sleeve R.

The free spindle device is an improvement on that illustrated in my Patent Number 865,007, in that it is better adapted to manufacturing methods, and easier to assemble.

By the use of the bracket device shown by Fig. 2, the same vertical adjusting elements described in my Patent Number, 865,007 and illustrated by Fig. 1, may be used either on 105 the front face of the window casing Z, as shown by Figs. 5 and 7, or on the interior face Z' of the casing, as shown by Fig. 6. In order to make this change it is only necessary to change the bracket from the position G' 110 H' to G H, Fig. 1, by withdrawing the portion F from its socket in block B, turning it

through 90 degrees and again inserting it in socket. This improvement therefore necessitates but a single construction of the vertical adjusting device, in order to make it applicable to either of the described locations on the window casing.

While the bracket construction described having the squared portion F, arranged to fit a square socket is preferred, I do not desire 10 to be limited to this particular form, as any plug and socket design which will allow the plug of the bracket to be locked in 90 degree positions will attain the same result.

I do not, therefore, wish to limit myself to 15 the precise forms and constructions shown, but

Having described this form of my invention, I claim as new, and desire to secure by Letters Patent:

1. The combination, in a shade and curtain adjuster, of a vertically guided and adjustable block B having a square socket

formed in the upper end thereof, with a plug fitting said socket, and arms G and H ending in pins N and M formed as part of said plug, 25 substantially as described.

2. In a shade and curtain adjuster, the combination of a vertically adjustable element having a socket therein, a plug adapted to said socket, and so formed as to lock in 30 ninety degree positions, with shade and curtain supporting arms formed as part of said plug and ending in vertical pins.

3. In a shade and curtain adjuster, the combination of a vertically guided and adjustable block B, a double armed bracket adjustable to ninety degree positions attached thereto, with a shade roller end formed of spindle piece P Q, sleeve R, radial arms V, and attaching points T.

RUDOLPH A. BREITENFELD.
